[57] ABSTRACT

A rotatable drying drum is provided with a drum wall having insertions and a combustion means for natural or liquid gas so that stone minerals can be dried and heated for the preparation of bituminous building materials. The combustion means includes a plurality of individual burners which are located in an end region of the drying drum.

ROTATABLE DRYING DRUM

BACKGROUND OF THE INVENTION

This invention is related to a rotatable drying drum for drying and heating stone materials for the preparation of bituminous building materials. The drying drum has a drum wall that is provided with insertions and has a combustion means for natural or liquid gas. Such drying drums are well-known. They serve to dry and to heat stone minerals of the different grain sizes. During the manufacturing process of bituminous building materials, bitumen and other materials are added to the heated stone minerals.

Drying drums of this kind are operated in the one-direction mode as well as in the counter-current mode. At one end of the drum, centrally in its front wall, there is located a burner that is directed into the interior of the drum and that, for example, can be heated with oil or gas. The central supply of the energy medium, oil or gas, requires a relatively high temperature for the firing space in the region of the firing and burning-out area. Displacement of the burning-out area, may lead to an incomplete combustion. When oil is used as a fuel, there is the danger of a carbon deposit and of an oil-mist deposit on the drying material. When gas is used, there is the danger of an incomplete combustion of the gas/air mixture with subsequent puff-effects in the exhaust pipes.

During the drying and heating process of stone minerals of the different grain classifications, the following problems are encountered. The power requirements of present day equipment exceed several hundreds of tons per hour. The use of hot bitumen and the preparation of melted asphalt require final temperatures greater than 180°C. For this purpose the heat requirements are already in the range of 25,000 kw/hr. The exhaust gas quantities of more than 100,000 m³ should be purified to an extent of less than 150 mg/m³ because of the safety conditions for protecting the environment. Because of environment protection, the use of fuel oil is only possible under special safety conditions in order to prevent the oil from penetrating the ground. Furthermore, the exhaust gases should not contain sulphurous or phosphorous compounds.

SUMMARY OF THE INVENTION

It is the principal object of this invention to overcome the shortcomings of the prior art and to improve a drying drum of the initially described kind such that a better solution to the aforementioned complex problems is given. It is especially of importance to assure a good combustion of the combustion gases. Furthermore, the drying drum should be usable for the different grain classifications.

According to the invention, this object is achieved by providing a rotatable drying drum with combustion means composed of a plurality of individual burners that are located in a final region of the drying drum. The individual burners of the combustion means are located in the region of the front wall and the adjacent cylindrical wall of the drying drum. According to a preferred embodiment, about half the length of the cylindrical wall of the drying drum is occupied by individual burners. In the region of the cylindrical wall of the drying drum, each of the individual burners is inclined against the direction of rotation of the drying drum at

an angle of about 45° with respect to a tangent to the cylindrical wall of the drying drum. Insertions comprising relatively small boxes are provided between the burners, while that part of the cylindrical wall of the drying drum not occupied by burners has insertions comprising relatively large boxes. The individual burners have separate outlet cross sections for the gas and the combustion air.

The inventive rotating drying drum has several advantages over the prior art. By dividing the combustion means into a plurality of individual burners a better control of the combustion process is possible. For example, it is possible to combust without excessive air, while the preparation of the gas/air mixture can be accomplished substantially more accurately than with the prior art. Furthermore, a large surface of flames is provided in order to achieve a good heat transfer. Thus, relatively cool exhaust gases can be taken from the drying drum and can be supplied directly to a filtering means. By distributing the burners along a part of the cylindrical wall of the drying drum a rather extensive heat exchange is made possible because of the direct contact. Adaptation of the individual burners to the various grain size classifications does not cause any difficulties, as power changes in the combustion can be controlled simply. In the region of the burners, the insertions comprise relatively small boxes in order to transfer as much as possible of the heat by contact. In the part of the drum that is not occupied by burners, the heat has to be transferred substantially by convection. This is achieved by using insertions that comprise relatively large "lifting" boxes and therefore effect an intensive movement of the materials to be heated. The stone minerals are picked up by the boxes and are moved in a free fall. Thus, convective heat is transferred by the heating gases to the stone minerals. The permanently free-burning burners in the upper region of the drying drum prevent an expiration of ignition of the ignitable gas/air mixture in the part of the drum that is covered by stone minerals since the free-burning burners permanently act as ignition burners. By the simple control of the pressure of the gas and combustion air it is possible to optimize the drying effect during the drying process of the homogeneous individual grain sizes.

DESCRIPTION OF THE DRAWINGS

This invention can be incorporated in several constructive embodiments. It is illustrated by means of the enclosed drawings, in which:

FIG. 1 is a longitudinal sectional view through a drying drum according to the preferred embodiment of this invention; and

FIG. 2 is an enlarged cross-sectional view of the drying drum of FIG. 1.

DESCRIPTION OF THE PREFERRED EMBODIMENT

As shown in FIGS. 1 and 2, the drying drum is constructed in a usual manner. It has a cylindrical side wall 1 with end regions which pass over into back and front walls 2 and 3. The drying drum is located in a substantially horizontal or slightly inclined position. It is rotatable and has a usual drive means. A material inlet is provided in the back wall 2 as indicated by the arrow 4, and a material outlet for the dried and heated stone

minerals is provided in the front wall 3 as indicated by the arrow 5.

In accordance with the preferred embodiment of this invention, a plurality of individual burners 6 are provided in the region of the material outlet when the drying drum is operated in the countercurrent mode. Preferably, the individual burners 6 are distributed over the front wall 3 and over about half of the length of the cylindrical wall 1 of the drying drum. Between the burners 6 are insertions 7 comprising relatively small lifting boxes. In the remaining part of the drum, which is not occupied by the burners 6, there are located insertions 8 comprising relatively large lifting boxes in order to cause an intensive movement of the material. The burners 6 and the insertions 7 and 8 are indicated schematically. The burners 6 have two separate known outlet cross sections for gas and for air. The insertions 7 and 8 are also constructed in a known manner. The heated gases are taken off in the direction of the arrow 9. Of course, when the drum is operated in the one-direction mode, the direction of the flow of material will be opposite from that indicated in the drawing.

It is essential that the combustion means be subdivided into a plurality of individual burners in order to obtain a better control of the gas/air mixture and to improve the mixing and combustion results. For example, a combustion without excessive air is made possible. This results in the maximum temperature that can be obtained with the combustion. A good control capability of the combustion means allows the specific treatment of each grain size. In summary, the heat transfer is substantially improved such that exhaust gases can also be purified without repeated cooling.

I claim:

1. Apparatus for drying and heating stone minerals for the preparation of bituminous building materials, said apparatus comprising a rotatable drying drum, a pair of material transfer ports positioned in a pair of opposite end portions of said drying drum, a first plurality of material lifting members mounted within said drying drum along a first side portion thereof adjoining one of said end portions, a second plurality of smaller material lifting members mounted within said drying drum along

a second side portion thereof adjoining the other of said end portions, and a plurality of individual burners mounted within said drying drum along said second side portion thereof with said smaller material lifting members and along said other end portion.

2. Apparatus as in claim 1 wherein said second side portion of said drying drum extends over about half the length of said drying drum.

3. Apparatus as in claim 1 wherein said burners are inclined against the direction of rotation of said drying drum at an angle of about 45° with respect to a tangent to said drying drum.

4. Apparatus as in claim 1 wherein said burners have separate outlet cross-sections for a combustion gas and for air.

5. Apparatus as in claim 1 wherein said material lifting members comprise material lifting boxes.

6. Apparatus as in claim 1 wherein said drying drum includes a cylindrical sidewall and a pair of end walls adjoining opposite ends of said cylindrical sidewall, said pair of material transfer ports is positioned in said end walls, said first plurality of material lifting members is mounted along a first portion of said cylindrical sidewall adjoining one of said end walls, said second plurality of smaller material lifting members is mounted along a second portion of said cylindrical sidewall adjoining the other of said end walls, and said plurality of individual burners is mounted along said second portion of said cylindrical sidewall and said other end wall.

7. Apparatus as in claim 6 wherein said second portion of said cylindrical sidewall extends over about half the length of said drying drum.

8. Apparatus as in claim 7 wherein said burners are inclined against the direction of rotation of said drying drum at an angle of about 45° with respect to a tangent to said cylindrical sidewall.

9. Apparatus as in claim 8 wherein said burners have separate outlet cross-sections for a combustion gas and for air.

10. Apparatus as in claim 9 wherein said material lifting members comprise material lifting boxes.
